200,411

SEWING MACHINE CABINET OR SIMILAR ARTICLE

Edward W. Stanton, Cranford, and Henry J. Milan, Clark,
N.J., assignors to The Singer Company, New York,
N.Y., a corporation of New Jersey

Filed July 18, 1963, Ser. No. 75,867

Term of patent 14 years

(Cl. D33—12)

Fig.1

Fig.2

FIG. 1 is a front perspective view of a sewing machine cabinet, showing our new design as it appears when the cabinet is closed, and

FIG. 2 is a front perspective view of the sewing machine cabinet shown in FIG. 1, on a slightly larger scale, and showing our new design when the cabinet is open and with the central panel insert, shown in FIG. 1, removed.

The outer unshown surface of the rear wall and the outer unshown surface of the side wall are plain.

We claim:

The ornamental design for a sewing machine cabinet or similar article, substantially as shown and described.
